Fig.1

Fig.2

FIG. 1 is a perspective view of a hand-puncher showing my new design; and

FIG. 2 is a rear perspective view thereof.

The bottom of the hand-puncher is plain and unornamented.

The characteristic feature of my design resides in the fact that the two punches are housed in two boxlike compartments fixed at opposed ends of the bed plate of the hand-puncher.

I claim:

The ornamental design for a hand-puncher, as shown and described.
